(57) **CLAIM**

The ornamental design for a telephone, as shown and described.

DESCRIPTION

[FIG. 1 is a perspective view of a telephone in accordance with my design;]

[FIG. 2 is a front view thereof;]

[FIG. 3 is a rear view thereof;]

[FIG. 4 is a left view thereof;]

[FIG. 5 is a right view thereof;]

[FIG. 6 is a top view thereof; and,]

[FIG. 7 is a bottom view thereof.]

FIG. 8 is a perspective view of a telephone in accordance with my design;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines in the drawings represent unclaimed environmental subject matter.

1 Claim, 3 Drawing Sheets

Matter enclosed in heavy brackets [ ] appears in the original patent but forms no part of this reissue; matter printed in italics indicates the additions made by reissue.
